UNITED STATES PATENT OFFICE.

AUGUSTUS ALGOEVER, OF NEW YORK, N. Y.

IMPROVEMENT IN WIRE-WORK FOR FENCES, &c.

Specification forming part of Letters Patent No. 37,266, dated January 6, 1863.

To all whom it may concern:

Be it known that I, AUGUSTUS ALGOEVER, of the city, county, and State of New York, have invented a new and improved mode of constructing wire fences, the main meshes of which may consist of hexagonal form, and which at the same time constitute the locking device which sustains and holds the wires in position of which the fence is composed; and I do hereby declare that the following is a full and exact description thereof, reference being had to the accompanying drawings, and to the letters of reference marked thereon, like letters in the several figures indicating the same or analogous parts, and in which drawings—

Figure 1 is a front view of a wire-fence panel illustrating different modes of employing my invention. Fig. 2 is a perspective view of a portion of the same. Fig. 3 is an elevation of one of the corrugated or crimped wires. Fig. 4 is a section in the line *x x* of Fig. 1, showing the wires as they appear before being hammered down. Fig. 5 is a section in the same line of Fig. 1, but of the panel after it has been subjected to the blow of a hammer at the different points of intersection of the wires. Fig. 6 is an end view of a portion of a panel as the wires appear before being hammered down at the points where they intersect one another. Fig. 7 shows the same as Fig. 6, but the wires have been hammered down at their points of intersection. Fig. 8 is an elevation of a portion of a panel partly wrought.

Similar letters of reference in the several figures indicate corresponding parts.

To make a wire panel for a fence, I take straight rods of wire, and at intervals along their length form, by bending or crimping, three depressions, two, *a a*, on one side, and one, *b*, on another side, the depression *b* being between the depressions *a a*, as shown in Fig. 3. The depth of each depression is a little greater than one-half the diameter of the wire rod. Wire rods thus crimped I take in pairs, and place them diagonally to a straight edge or perpendicular, a short distance apart, as indicated at *c c*, so that the intermediate depressions *b* are up and the depressions *a a* down. I then take other pairs of such rods and place them diagonally in a converse order to those *c c* across the rods *c c*, as indicated at *d d*, so that the intermediate depressions, *b*,

shall be down and directly over the intermediate depressions of the rods *c*, while the depressions *a a* are up and between the rods *c c*. The upper and lower rods thus arranged inclose diamond spaces between their points of intersection, both within and outside of the same, as indicated at *e e*, Fig. 8. They also inclose rhomboidal spaces, as indicated at *f f* in same figure. The depressions *b b* of the rods, by coming together and allowing the rods *c c* and *d d* to touch at the point of intersection, cause the depressions *a a* of the upper and lower rods to form between themselves passages *g*, of a size a little greater than the diameter of one of the rods. I next take straight or uncrimped rods *h h*, and insert them between the upper and lower diagonal pairs of rods, *c d*, by passing them in a direction at right angles to a perpendicular through the passages *g*, formed by the depressions *a* in the rods *c* and *d*, as indicated in Fig. 6 and in Figs. 2 and 4. The three sets of rods thus arranged divide up the spaces between them into hexagons *i i*, oblong hexagons *j j*, and large triangles *k k*, and small triangles *l l*, as represented in Fig. 1. The panel thus formed is in thickness, at all of the points of intersection, a little greater than three layers of wire, and in order to lock the wires firmly at all of the points of intersection I place the panel flatwise upon an iron platform, and apply the force of a hammer upon the intersecting portions until the thickness of the panel at said points is reduced down to two layers of wire, as illustrated in Figs. 5 and 7. The force of the hammer with the resistance of the platform causes the corrugated portions of the wires *c d* to bend the straight wires *h h* in the same manner as they themselves were bent before being applied. Thus the whole are interwoven together in an undulating manner, and cannot possibly separate or move independently of each other; and beside this, great stiffness is imparted to the panel, and the aid of cast ornaments to stiffen and hold the wires rendered unnecessary.

In Fig. 1, at *m m*, I have shown a method of locking the diagonal wires together with short sections of parallel rods. By this plan a more open fence can be formed, as is indicated at *n n*, and still the panel will be stiff and secure in its connections. The same principle of tying diagonal wires may be employed

in forming small rosettes or buttons for ornamenting other styles of wire-fence panels, and for aiding in tying the wires together at their points of intersection.

In bending the wires, Fig. 3, they may be bent with the sets of depressions *a a* and *b* in closer or farther relation to one another along the length of the wire, so as to suit the style of panel or other open-work into which they are to be wrought.

The extent and style of the bend or corrugation may be varied to suit circumstances, and it may be accomplished by dies or by hand—that is, the diagonal wires—the straight wires being, of course, bent after they are applied, substantially as described.

My method of constructing wire fence and other wire-work will meet the long demand for a light, stiff, durable, and ornamental fence at a small cost. Any skillful farmer or

other person can purchase the wire and bend it and set it up with ease and dispatch, or the corrugated wire, Fig. 3, can be sold in the market almost as cheap as the straight article.

Having thus described my invention, what I claim as new, and desire to secure by Letters Patent of the United States, is—

The method of constructing wire fence and other wire-work by first crimping a portion of the wires to be used in such a manner that, being laid in a proper position for the work intended to be made, the indentations formed in them will admit of the insertion of straight wires in such manner that they will form a lock to the whole when finished, substantially as described.

AUG. ALGOEVER.
